UNITED STATES PATENT OFFICE.

JOHN H. VINTON, OF BOSTON, MASSACHUSETTS, ASSIGNOR TO THE PENINSULAR NOVELTY COMPANY, OF GRAND RAPIDS, MICHIGAN.

BUTTON-SETTING MACHINE.

SPECIFICATION forming part of Letters Patent No. 328,365, dated October 13, 1885.

Application filed February 24, 1885. Serial No. 156,835. (No model.)

To all whom it may concern:

Be it known that I, JOHN H. VINTON, of Boston, county of Suffolk, and State of Massachusetts, have invented an Improvement in 5 Button-Setting Machines, of which the following description, in connection with the accompanying drawings, is a specification, like letters on the drawings representing like parts.

This invention has for its object to improve 10 the construction of that class of machines represented in United States Patent No. 312,987, dated February 24, 1883, especially in the construction of the mechanism to control the passage of the staples and attached buttons, one at 15 a time, from the staple-chute into the guide of the staple-carrier. I have also provided the carrier with a saddle for the legs of the staple, and with a spring to act against the end of the shank or eye of the button and arrest or hold 20 it midway the said guide until acted upon by the driver or former.

Figure 1, in side elevation partially broken out, represents a sufficient portion of a button-setting apparatus of the class referred to to 25 enable my invention to be understood, the carrier and driver being shown as descending, the driver being just ready to force the staple from the carrier into the material. Fig. 2 is an inside elevation of the carrier alone; Fig. 3, a 30 button and staple attached, ready to be placed in the staple-guide; Fig. 4, a detail of the driver or former alone; Fig. 5, a top view of the staple-holding tube and part of the chute. Fig. 6 is a detail of the friction device removed, 35 and Fig. 7 is a cross-section of Figs. 1 and 5 in the dotted lines *y y*.

The main or stationary frame-work A, the anvil *a*, the horn *A'*, the rod *D*, its attached arm *D'*, the driver *c*, and the carrier, to be referred to, are substantially as represented in 40 the patent referred to.

The staple-chute *B'* is connected with a plate, *B*, attached to the frame-work by screws 22.

The slide-bar *d'*, to which the slotted guide 45 *d* is attached, the said bar and guide constituting the carrier, is guided in the bearing or box *A'* of the frame-work A, and in the bearings 57 and 59 of the arm *D'*.

The spindle 23, attached to the upper end 50 of the bar *d'*, is extended through a spiral

spring, 24, then through the bearing or box 59 of the arm *D'* and the friction device 60 thereon, and thence through a spiral spring, 25, above which the spindle is provided with a check-nut, 26, the spring 25 acting normally 5 to lift the carrier, and the spring 24 to permit it to be depressed in a yielding manner to enable the lower end of the carrier to strike against the material on the anvil in advance of the contact of the lower end of the driver *c* or former with the head or crown of the staple to be driven, the carrier when arrested by the material on the anvil stopping, while the driver or former continues to descend to drive the staple from the carrier. 6

In accordance with my invention I have provided the lower end of the slide-bar *d'*, within the carrier and opposite the open end of the staple-chute *B'*, with a saddle-piece, 27, astride of which the staple *s* will land as it 7 leaves the chute *B'* and enters the carrier, the said staple descending in the said carrier with its legs properly directed downward, and with the center of the crown of the staple in the eye of the button *b*, the staple hanging vertically. 7

Below the saddle I have provided the slide-bar with a button-holding spring or presser, 28, which acts against the end of the eye of the button a little below the center of the button, 8 thus checking or holding the button in the slot of the carrier midway thereof, while the latter descends to place its lower end against the material, and while the driver or former is descending to strike the staple. 8

The staples *s*, having buttons *b* attached, are preferably first fed by hand into a tube, *T*, which may be readily attached to the upper end of the chute *B'* in position to let the staples pass freely into the staple-chute *B'*, the 9 said staples, with attached buttons, sliding down the staple-chute until the shank of the button comes in contact with the detent *M*, pivoted at 31, and acted upon by a spring, 32, the latter normally keeping the point of the 9 detent in the slot of the chute *B'*.

A let-off, *L*, is pivoted at 34 on an ear, 35, of the plate *B*, a spring, 36, acting on the let-off, normally keeping its point in the slot of the staple-chute below the said detent. 10

The drawings show but one staple and attached button as held by the detent, another staple and button having passed the detent and being held by the let-off, while a third staple is shown as within the guide of the staple-carrier, the button being outside the said guide.

The arm D^2 has an ear, 37, provided with a projection, preferably an adjustable screw, 38, which, during the descent of the said arm from its position, Fig. 1, which is nearly its lowest position, strikes the projection 33 of the let-off L , turns it, and permits the staple held by it and its attached button to slide 5 down the staple-chute; but at this time it will be noticed that the driver e is in the carrier and about to drive the staple therefrom, and that the said driver then acts to close the opening through which the staple must pass 10 to enter the carrier from the end of the chute.

Just as the let-off is operated to permit the staple held by it to descend by gravity in the staple-chute, the driver or former e acts to drive the staple under it from the carrier in 15 and through the material supported on the anvil a , thus clinching the points of the staple.

After the staple has been driven and clinched the arm D^2 is raised, and with it the 20 driver e , and the carrier is lifted until the upper end of the guide d meets the box or bearing A^4 of the rigid arm of the frame-work, after which, in the further ascent of the said arm D^2 , the spring 25 is compressed, and 25 while the said guide d remains at rest the driver or former is raised sufficiently to uncover the end of the staple-chute B' and the entrance into the carrier-guide, and during 30 the yet further ascent of the arm D^2 and the 35 lug 37 the latter strikes the pivoted block 30 of the detent M , lifting it in the direction of the arrow thereon, but without turning the 40 detent M on its pivot.

In practice the end of the ear 37 passes 45 above the portion 30 of the detent M , and when the arm D^2 is again depressed the said ear strikes the block 30 and turns the detent before the screw or projection 38 meets the let-off L , such movement of the detent during 50 the descent of the arm D^2 permitting the button held by the detent to descend against the let-off, which holds the staple and button-eye above it until in the further descent of the arm D^2 the projection 38 strikes the portion 55 33 of the let-off, the movement of the latter permitting the staple and button held by it to pass the let-off and slide down the chute against the driver.

The saddle 27 may be a separate piece, as 60 shown, or be integral with the spring 28.

The tubes T (a number of which are employed with each machine) may be filled and kept ready to be applied to the upper end of the chute B' , a filled tube being applied to 65 the chute whenever necessary. The tube T is slotted from end to end at its lower side,

(see Fig. 7,) and has at its ends spring stops or catches t^2 , portions of which normally enter notches in the tubes and act to retain the staples in the tubes while the latter are 70 being handled.

The spring t^2 has a projecting finger, 58, which as the tube T is applied to the open upper end of the chute B' rides upon the cam 39 at the upper end of the detent, as in Fig. 75 1, the said cam lifting the spring and removing its lip or projection 40 from the tube, permitting the staples and buttons to readily pass into the chute, one staple and button being shown by dotted lines. 80

The friction device 60, made as a slotted block held in place by the bearing 59, may be made to pinch the rod 23 more or less snugly by turning the adjusting device 61. (Shown as a screw, see Figs. 1 and 6.) This 85 friction device may be made to pinch the rod sufficiently close to enable the latter by the friction device to travel in unison with the arm D^2 as it rises and falls, so long as the movement of the carrier is not arrested by 90 some device not a part of the said arm D^2 —as, for instance, when in the descent of the arm D^2 the lower end of the carrier meets the material on the anvil the carrier is stopped, and thereafter the arm D^2 and the friction device slides down upon the rod 23, and it slides 95 upward on the said rod after the carrier, in its upward movement with the said arm D^2 , strikes the box A^4 .

The hinged block 30 prevents the turning 100 of the detent as the driver rises, and obviates accidental forcing of the staple above it and lessens the liability of getting two staples and buttons at one time in the guide.

I claim—

1. The chute, the detent, and the let-off, combined with the movable arm, and its ear and screw or projection to act upon and turn the detent and the let-off, substantially as described.

2. In a button-setting apparatus, the staple-chute, the bar d' , and its attached slotted guide d , provided with the saddle astride of which the staple passes as it leaves the chute, combined with the spring to act upon the eye of the button, substantially as described.

3. In a button-setting apparatus, the staple-chute, the bar d' , and its attached slotted guide, combined with the spring attached to said guide, to act upon the eye of the button, substantially as described.

4. The independent tube T , slotted at its under side, and provided at its ends with catches, combined with the chute, to operate substantially as described.

5. The tube T , slotted at its underside, and provided with the stop or catch t^2 , combined with the chute B' , and a cam or projection to lift the stop or catch and permit the passage of fastenings and buttons from the tube into 130 the chute, substantially as described.

6. In a button-setting machine, the arm D^2 ,

105

110

125

the driver, and the carrier, combined with the springs 24 and 25, to operate substantially as described.

7. The arm D², the driver, and the carrier, combined with the friction device to act against the rod of the carrier, substantially as described.

8. The chute and the detent provided with a hinged or pivoted block, 30, combined with

the projection to operate the said detent, substantially as described.

In testimony whereof I have signed my name to this specification in the presence of two subscribing witnesses.

JOHN H. VINTON.

Witnesses.
